UNITED STATES PATENT OFFICE

ALBERT L. SANDEL, OF CHICAGO, ILLINOIS

DESIGN FOR A LAMP

Application filed July 11, 1932. Serial No. 44,303. Term of patent 3½ years.

To all whom it may concern:

Be it known that I, ALBERT L. SANDEL, a citizen of the United States, and resident of Chicago, in the county of Cook and State of Illinois, have invented a new, original, and ornamental Design for a Lamp, of which the following is a specification, reference being had to the accompanying drawing, forming a part thereof.

The figure is a side elevational view of a lamp showing my new design.

The shade is a pleated taffeta shade, having the same appearance on both sides thereof and being of generally oval configuration, open at the bottom.

I claim:

The ornamental design for a lamp, substantially as shown and described.

Signed at Chicago, in the county of Cook and State of Illinois, this 31st day of May, A. D. 1932.

ALBERT L. SANDEL.
